UNITED STATES PATENT OFFICE.

OKE A. SHONBECK, OF KANSAS CITY, MISSOURI, ASSIGNOR OF ONE-HALF TO
LYSANDER R. MOORE, JR., OF SAME PLACE.

GRAIN-SCOURER.

SPECIFICATION forming part of Letters Patent No. 660,205, dated October 23, 1900.

Application filed April 23, 1897. Renewed March 29, 1900. Serial No. 10,702. (No model.)

To all whom it may concern:

Be it known that I, OKE A. SHONBECK, a citizen of the United States of America, residing at Kansas City, in the county of Jackson and State of Missouri, have invented certain new and useful Improvements in Grain-Scourers; and I do hereby declare that the following is a full, clear, and exact description of the invention, reference being had to the accompanying drawings, forming a part of this specification.

My invention has for its objects, first, the repeated scattering of the grain and its contact with all of the scouring-surfaces of the scouring-body; second, to regulate the scouring process to which the grain is subjected automatically within certain intervals of time; third, to regulate feed of the uncleared grain simultaneously with the automatic closing of the discharge-openings in the scouring-case, and, fourth, to discharge automatically the scoured grain from the scourers at the proper time.

My invention consists in the novel construction and combination of parts, such as will be first fully described, and specifically pointed out in the claims.

In the drawings, Figure 1 is a view in perspective of the grain-scourer embodying the invention, with a portion of the frame and dust-catching box broken away to show the novel parts. Fig. 2 is a horizontal sectional view of the improved scourer, taken upon line xx of Fig. 3. Fig. 3 is a vertical sectional view of the improved scourer. Fig. 4 is a detail view in perspective of the novel grain-scourer removed from the frame, showing also the feed-receptacle for the grain broken away to show the valved openings for the passage of the grain and the automatically-operated levers controlling the valves. Fig. 5 is a detail sectional view of a portion of the perforate scouring-case, showing the door and latch-bolt and lever and a sectional view of the worm-wheel and worm and also showing the latch-releasing plate in position to operate the lever.

Similar letters of reference indicate corresponding parts in all the figures.

50 A represents the frame supporting the grain-scourer, consisting of the horizontal

base-beams a a , arranged at the proper distance apart, the upright beams a^2 a^2 , extending from each end of the beams a a , and the horizontal shaft-supporting beams a^3 a^3 for 55 the grain-scourer, connected with the upper ends of the beams a^2 a^2 .

B is a shaft extending transversely to the beams a^3 a^3 and rotating within the journal-boxes a^4 a^4 upon the upper side of said beams, 60 which journal-boxes are nearly equidistant from the ends of said beams a^3 in position.

Upon the rotary shaft B is fixedly mounted a circular grain-scouring body or wheel C, preferably composed of hard sandstone of 65 considerable width. The scouring-wheel C rotates within and independently of an exterior circular case D, which is constructed as follows: At the axis and upon each side of case D is an outwardly-extended flange d , of 70 considerable width, which forms the journals for the said case, the diameter of the flange being such as to afford a large opening concentric with the shaft B. On the inner side of flange d is a collar d' , with the inner side 75 of which collar are connected the spokes d^2 , which extend radially from a line drawn in the plane of the flange d to an outer rim d^3 , with which they are rigidly connected, the circumference of the periphery of said rim 80 being in excess of the circumference of the scouring-wheel C, as further described.

On the inner side of each shaft-supporting beam a^3 is a block a^5 , with the inner side of which block is rigidly connected a disk E, in 85 which is an opening e at the center, through which the shaft B is passed. Extending around the circumference of the disk E, the line of which circumference is slightly in excess of the circumference of the flange d on 90 the case D, is an inwardly-extended annular flange e' , which receives the said flange d and forms a closely-fitting journal-bearing therefor on the inner side of the spokes d^2 and the rim d^3 . On each side of the case D is a circular perforated plate F, having an opening f of the same size and opposite in position to the collar d' on the side of the said case, the outer edge of the plate F being in line circumferentially with the outer edge of the rim 95 d^3 . The perforations f^x in the side of the plate F are made by punching the sides of each

perforation inwardly, leaving the ragged edge turned toward the stone C.

The peripheral portion of the case D is composed of a wide plate f^2 , extending circumferentially around the case and having its longitudinal edges secured to the circular outer edges of the rims d^3 , the width of said plate being in excess of the width of the scouring-wheel C, so as to leave a space f^0 between the sides of the scouring-wheel C and the inner sides of the plates F F and between the periphery of the scouring-wheel and said plate f^2 . The plate f^2 is perforated in the same manner as the plates F F. In the plate f^2 is an opening f^3 , extending from one side F to the other side of said case E and the proper distance in length to discharge the grain, which opening is closed by a door or valve f^4 , which is hinged at f^5 at one end to the edge of the opening f^3 , transverse to the case E. On the outer side portion of the door is a fixed wedge-shaped plate or cam f^6 , the widest portion of which cam terminates within a short distance of the free edge of the door f^4 . Above the free edge of the door is a latch-case f^7 , in which is a latch-bolt f^8 , which bolt is caused to engage with the said free edge of the door f^4 by a spring f^9 . With the upper end of the latch-case is pivotally connected one end of a lever f^{10} , which lever is also pivotally connected with the adjacent end of the latch-bolt, the other end of said lever extending a short distance outwardly beyond the line of the outer side of the latch-case, for the purpose hereinafter described.

Extending around the case E in line with one of the rims f^3 is a circular rack G. At one end of the frame A and journaled at h upon the shaft-supporting beams $a^3 a^3$ at a point a short distance from the case E is a transverse shaft H, upon which shaft is a pinion h' , engaging with the rack G on case E. On the outer end of said shaft, extending beyond the outer side of beam a^3 , is a band-wheel h^2 . Between the side beams $a^2 a^2$ and $a^3 a^3$ and connected at their upper edges with the beams $a^3 a^3$ are the sides $i i$ of a dust-inclosing case I, which sides extend downwardly nearly to the line of the beams $a a$ and the lower ends inclined downwardly toward each other at $i' i'$ and is also provided with the ends i^2 and bottom i^3 . The upper portion I' of the dust-inclosing case is removable from the lower portion, being separated from the lower portion upon a line horizontal with the upper surfaces of the beams $a^3 a^3$.

Within the lower portion I of the dust-inclosing case and beneath the shaft H is a transverse beam K, secured at the ends of the inner sides $i i$ of the portion I of the dust-inclosing case and about equidistant from the peripheral line of case E and the adjacent end i^2 of said case I. Upon the upper portion of beam K is a base-plate M, upon each end of which plate are arms $m m$, extending in the direction of the rotary case E, and upon the outer ends of which arms is journaled at n

a shaft N, upon which shaft, between said arms $m m$, is a worm-gear n^2 . The end of shaft N extends a short distance beyond the plane of the side of case E opposite to that having the curved rack G, and upon said end is a fixed hub n^3 , upon the circumference of which hub are the radial arms n^4 . Upon the outer side of rim d^3 of the rotary case D and upon the segmental portion of said rim, within which the door f^4 in said case is located, are pins d^4 , arranged an equal distance apart and which come into contact with the outer ends of the arms n^4 on the hub n^3 of shaft N and 80 actuate said shaft during the time the portion of the rim containing the series of pins is passing within the radius of the hub n^3 on said shaft.

Upon the bed-plate M is a pivot-post m^2 . Above the said plate is a horizontal worm-wheel O, which meshes with the worm n^2 on shaft N. Through the axis of wheel O extends a socket o , which receives the pivot-post m^2 .

Upon the upper side portion of the worm-wheel O is a longitudinally-slotted latch-releasing plate P, secured adjustably to said worm-wheel by the adjusting-screw p , the forward end of which plate is extended a short distance beyond the periphery of said worm-wheel and within the path in the circle of rotation of case D described by the outer end of the latch-bolt-releasing lever f^{10} to the door f^4 in the peripheral portion of the rotary case D. Other plates P are secured adjustably to the worm-wheel in radial lines from the pivot-post m^2 and at equal distances from each other in the series extending around the worm-wheel and which also come into contact successively with the latch-bolt-releasing lever f^{10} , this mechanism regulating the time for treating the grain in the scouring process. At the other end of the frame A of the machine and within the lower portion I of the dust-inclosing case is a transverse non-rotating shaft X, fixedly connected with the sides $i i$ of said portion of the case, and upon which shaft is a circular casting X', the curved outer edge portion of which is located in the path of the cam f^6 on the door f^4 and close enough in position to said door when open to effect an engagement of the latch-bolt f^8 with the free edge of the door.

R is the feed-hopper on the outside of the dust-inclosing case and elevated the proper height to receive and distribute the grain to the scouring-case D. In the bottom of the hopper are openings r for the passage of the grain, each opening describing the segment of a circle. Above and closing said openings is a wheel or valve r' , having openings r^2 , describing segments of a circle alternate in position to the openings r . With the lower end of hopper R is connected the upper end of a conductor or chute r^3 , the lower end of which chute inclines toward and extends through the disk E on the side of the rotary case opposite to that having the circular rack G.

With the axis of the wheel r' is connected a shaft r^4 , which extends downwardly through the bottom of chute r^3 , and upon the lower end of said shaft is a crank r^5 .

5 Upon the beam a^3 , a short distance toward the end of said beam from that having the shaft H , is a fixed upright post S , upon the upper end of which post is pivoted horizontally a double-armed lever T , one arm of said 10 lever being extended through a slot t in the side of the portion of the dust-inclosing case I' and nearly in contact with the side of the rotary scouring-case D . With the other end of said arm is connected a link t^2 , which is 15 also connected with the crank r^5 on the shaft r^4 , operating the wheel r' in the feed-hopper R . On the side of the rotary case D and in the path of the inner portion of the double-armed lever T , extending through the slot t 20 in the side of case I , is a fixed curved guide plate or arm U , secured edgewise to the side of the said case by lugs u on the inner edge of the guide-plate U , the said guide-plate being in a line eccentric with the periphery of case D and situated upon a portion of the side of the case opposite to that in which the door f^4 is located for dropping the cleaned grain, the position of said guide-plate being such as to permit the end of the guide 25 nearest the axis of the case to throw the end of the lever in contact therewith, also toward the axis of the scouring-case, and consequently the action upon the link t^2 and crank r^5 will rotate the wheel r' and close the openings r in the bottom of the hopper R . Upon 30 the same side of the case D and opposite thereto in position is a separate curved slotted plate or can V , secured to the spokes d^2 by adjusting-screws v and with one end in a position nearer the axis of the case D than the other. Upon the upright beams a^2 at the 35 end of case A having shaft H and journaled in the boxes w a short distance above the line of the ends of the beams a is a transverse shaft W , upon one end of which shaft, beyond the side of the frame A , is a small-sized belt-pulley W' , over which extends one 40 end of a belt w^2 , the other end of which belt is extended over the pulley h^2 on the shaft H and the ends connected together in the usual manner, said pulley h^2 being larger in size 45 than the pulley W' . On the said shaft W is also secured close in position to the pulley W' a pulley w^3 , nearly twice the size of the pulley W' . Over the pulley w^3 is extended one end of a belt w^4 , the other end of which belt is twisted once and extended over the 50 small pulley b on the end of shaft B and the two ends connected together in the usual manner.

Upon the other end of the shaft B from that having the pulley b is a large band-wheel B' , over which is extended one end of a belt b^2 , the other end of said belt being extended 55 to and over the pulley upon the shaft of the engine conveying power to shaft B , (not shown,) and which ends of the belt are se-

cured together in the usual manner. The power communicated to the shaft B from a suitable source is communicated to the scouring-wheel C and the wheel caused to rotate in the direction indicated by the arrows in Figs. 1 and 4 or toward the shaft H and at a degree of speed approximating to several hundred revolutions per minute. At the same 70 time motion from shaft B is communicated through the belt w^4 to the band-pulley w^3 and thence to the shaft W , and from shaft W a slower degree of speed is communicated through the small pulley W' and through the 75 belt w^2 to the pulley h^2 on the shaft H , which shaft actuates the pinion h' , meshing with the rack G on the case D , and the said case is rotated in the same direction as the scouring-wheel C at a very slow degree of speed, 80 approximating to several revolutions per minute.

In the rotation of the case D and when the pins d^4 upon the portion of the rim d^3 strike the arms n^4 on the hub n^3 of the shaft N the 90 worm n^2 will actuate the worm-wheel O , which turns upon its pivot at a slow degree of speed, it being apparent that in order that the worm-wheel shall move a distance upon the line of the radius past the lever f^{10} equal to the distances between the outer ends of adjacent tripping-plates P on the worm-wheel the case D will describe approximately four revolutions. The uncleaved grain to be scoured is 95 fed or conveyed to the hopper R , the said hopper containing the approximate amount of grain which can be treated within certain intervals of time, the door f^4 in the case D for the purpose of illustration being closed and the wheel r' in the hopper R turned to 100 admit the grain to the scourer, as in the position in Fig. 4 of the drawings. In this position the inner end of the lever T is upon the inner side of the guide U and at the end farther removed from the axis of the case D . 110 As the wheel continues to revolve the end of the lever is thrown inwardly toward the axis of the said case, closing the openings r in the hopper, which openings remain closed until the end of the lever meets the outer edge of 115 the guide V at a point a short distance from the end of said guide closest in proximity to the axis of the case D , when the arm is thrown in an opposite direction and the openings exposed in the hopper to admit another charge 120 to the scouring-case, this reciprocal movement of the end of the lever being repeated at each rotation of the said case D . The grain admitted to the chute r^3 falls by gravity within the space f^0 between the sides of 125 the scouring-wheel C and case D and upon reaching the part of said case D lowest in position is immediately carried upward by the movement of said case D and scattered over the periphery of the scouring-wheel 130 and into the space between the sides of said wheel C and case D . The uncleaved grain in this condition is brought into contact with the sides of the scouring-wheel C and with-

in the centrifugal air-currents caused by the rotation of wheel C. The grain coming in contact with the stone causes the removal of the outer chaff or bran, and the ends of the grain are presented as the centrifugal action is imparted to each kernel to eddies formed around each perforation f^x on the inner side of the case E, the ends of each kernel receiving a scouring in repeated contact with the rough or ragged edges of each perforation. During the rotation of the scouring-wheel C the disintegrations of the stone, which under the high degree of speed are thrown from the stone, as well as caused by the attrition of the grain on the stone, mix with the centrifugal air-currents and impart a scouring action to the grain. As soon as the charge of grain has been subjected to the scouring the interval of time required by the rotation of shaft N to bring one of the plates P in the path of the latch-bolt-releasing lever f^{10} the said lever is thrown upwardly, so as to release the latch and at the same time avoid further contact with the bar P, and the free end of the door f^4 falls outwardly and downwardly, and the scoured grain falls into the bottom of the portion I of the dust-inclosing case. In the next quarter of the circle of rotation of case E the cam f^6 meets the casting or obstruction x and the door is closed automatically, and the latch-bolt also latches the free end of the door. The operation as described in detail of feeding the grain to the scouring-case is then repeated, the number of rotations of the scouring-wheel and case D being performed in which to effectually scour the grain during the time required for the movement of the worm-wheel, so as to bring the next tripping-plate P in position in the path of the lever on the latch-bolt on the door f^4 , when the scoured grain is ejected as before. In order, however, to increase the length of time in which the grain is to be treated, a lesser number of plates P are required, and to effect this result the adjusting-screws p are released in every other plate P and the said plates moved back from contact with the lever on the latch-bolt and the plates secured in the adjusted position, leaving a wider space between the adjacent plates. When required, the number of plates may be increased, so as to cause a more rapid discharge of the grain. In my improved scourer I effect a thoroughly-cleaned grain, especially at the ends of each kernel, affording the removal of all of the external chaff and bran, which is forced during the operation through the perforations in the case E. As the stone C decreases in circumference from the wear in the scouring process I effect the reduction of the sides of case D, so as to keep the same width of space between the portion f of said case and the periphery of stone C, by cutting away the outer edge of the rim d^7 circumferentially in a corresponding degree to the wear of the stone. The scouring may

be done either with a sandstone wheel or a composition emery-wheel. In my scourer a definite amount of the uncleared grain is subjected to scouring before the admission of another charge. Consequently the impurities are all removed and the cleaned grain superior than hitherto obtained by other processes.

It is obvious that changes may be made within the scope of the invention of the devices for operating the worm-wheel and also feeding the unclean grain to the perforate case, and therefore I do not wish to be limited to the exact details of the various constructions.

Having fully described my invention, what I now claim as new, and desire to secure by Letters Patent, is—

1. In a grain-scourer comprising a grain-scouring rotary wheel and its driven shaft, an independently-rotating grain-scouring, perforate case extending around said grain-scouring wheel, having an opening for the reception of the uncleared grain in the end of said case, and a separate opening for the discharge of the scoured grain in the side of said case, a door to said latter opening hinged to the said case, a self-fastening device for said door upon said case, a cam on said door, and a door-closing device upon a suitable fixed support in the path of the cam on said door.

2. In a grain-scourer, the combination with the main frame of a grain-scouring wheel and its driven shaft, an independently-rotating grain-receiving case extending around said scouring-wheel, having an opening for the reception of the uncleared grain, and a separate discharge-opening, a door to said latter opening hinged to said case, a self-fastening device to said door upon said case, means substantially as described for rotating said scouring-wheel and case at different degrees of speed, and mechanism substantially as described upon said frame controlling the unfastening automatically of the fastening device to said door.

3. In a grain-scourer, the combination with the main frame of a grain-scouring wheel and its driven shaft, an independently-rotating grain-receiving case extending around said scouring-wheel, having an opening for the reception of the uncleared grain, and a separate discharge-opening, a door to said latter opening hinged to said case, and a self-fastening device for said door upon said case, means for rotating said scouring-wheel and case simultaneously and at different degrees of speed, mechanism substantially as described upon said frame controlling the unfastening automatically of the fastening device to the door, a door-closing device upon said frame in the path of the said door when in an open position, and a cam on said door in the path of the said door-closing device.

4. In a grain-scourer, the combination with the main frame of a grain-scouring wheel and its driven shaft, and an independently-rotat-

ing grain-receiving case, extending around said scouring-wheel, having an opening for the reception of the uncleared grain, and a separate discharge-opening, a door to said latter opening hinged to said case, a latch-bolt upon said case, and a tripping device upon said frame in the path of the latch-bolt.

5 5. The combination with a suitable frame of a rotary case journaled thereon, having a suitable discharge-opening, and a door thereto, hinged to said case, a self-acting door-fastening latch secured to said case, a shaft near the periphery of said case, a worm-gear on said shaft, a worm-wheel actuated by the worm-gear, power-conveyers connecting the said case with the said shaft, and latch-operating devices upon the worm-wheel in the path of and intermittently releasing the said latch, and means substantially as described for rotating said case.

10 6. The combination with a suitable frame, of a rotary case having a suitable frame, of a rotary case having a suitable discharge-opening and a door thereto, hinged to said case, a self-acting door-fastening device secured to the said case, means for rotating said case, a shaft near the periphery of said case, power-conveyers connecting said shaft and case adapted to impart intermittent rotation to the shaft, a worm upon said shaft, a worm-gear-wheel actuated by said worm-gear and adjustable radial plates upon said worm-wheel, in the path of and adapted to contact with and release the fastening device to the door upon said rotary case.

15 7. In a grain-scourer, a suitable frame, a rotary, perforate case, and a grain-scouring device within said case, said case having a suitable opening for the reception of the uncleared grain, and a discharge-opening, a door to said latter opening hinged to said case, a latch-bolt on said case for said door, a lever operating said bolt, a cam on said door, a power-driven shaft near the periphery of said case, power-conveyers connecting said shaft and case, a separate shaft near the said periphery of said case, a hub on said shaft, radial arms on said hub, and pins on the side of said case, adapted to contact with said radial arms, a worm on said shaft having said radial arms, a worm gear-wheel actuated by said worm, plates upon the said worm-wheel adapted to come into contact with the lever operating the latch-bolt on said door, in the

circle of rotation of the worm-wheel, and a stationary door-closing device upon the other side of the frame, in the path of the cam on said door.

8. The combination with a suitable frame of a rotary case having a suitable discharge-opening and a door thereto hinged to said case, a self-acting door-fastening device secured to said case, means for rotating said case, a shaft near the periphery of said case, a hub on said shaft, and radial arms on said hub, a worm upon said shaft and a worm gear-wheel actuated by said worm-gear, adjustable radial plates upon the said worm-wheel in the path of and adapted to contact with and release the fastening device to the door upon said rotary case, and pins upon the side of said case adapted to come into contact with the radial arms on said shaft and communicate an intermittent rotary motion to said shaft.

15 9. The combination with a rotary case having an annular opening in its side and at its axis, for the reception of the material to be treated and a valve discharge-opening, a hopper, a valve in said hopper, a conductor leading from said hopper to the said annular opening, a lever connected at one end with said valve, and cams upon one side of said case, adapted to come into contact with the other end of said lever alternately and also alternately open and close the valve in said hopper.

20 10. The combination with a rotary grain-scouring case, provided with axial annular flanges and its supporting-frame, of disks secured to the inner sides of said frame, and provided with annular flanges serving as bearings for the flanges on the said case, a hopper a valve in said hopper, a conductor connected with said hopper and extending through one of the said disks, a crank-shaft connected with said valve in said hopper, a support upon said frame, a pivoted lever upon said support having one end extending in the direction of the side of said rotary case and a link connecting said crank-shaft and the other end of said lever and curved guides upon the side of said case opposite in position, in eccentric planes adapted to contact alternately with the end of the said lever.
